US00D960900S

(12) **United States Design Patent** (10) **Patent No.:** **US D960,900 S**
Ofstad et al. (45) **Date of Patent:** **** Aug. 16, 2022**

(54) **COMPUTING DEVICE HAVING A GRAPHICAL USER INTERFACE FOR A MAP APPLICATION**

(71) Applicant: **GOOGLE LLC**, Mountain View, CA (US)

(72) Inventors: **Andrew Ofstad**, Mountain View, CA (US); **Willem Van Lancker**, New York, NY (US); **Matthew Robert Simpson**, San Francisco, CA (US); **Bernhard Seefeld**, San Francisco, CA (US)

(73) Assignee: **GOOGLE LLC**, Mountain View, CA (US)

(**) Term: **15 Years**

(21) Appl. No.: **29/751,569**

(22) Filed: **Sep. 22, 2020**

Related U.S. Application Data

(60) Division of application No. 29/722,964, filed on Feb. 3, 2020, now Pat. No. Des. 900,131, which is a division of application No. 29/626,930, filed on Nov. 21, 2017, now Pat. No. Des. 874,489, which is a continuation of application No. 15/362,580, filed on Nov. 28, 2016, now Pat. No. 9,852,534, which is a continuation of application No. 13/616,227, filed on Sep. 14, 2012, now Pat. No. 9,508,169.

CLAIM

The ornamental design for a computing device having a graphical user interface for a map application, as shown and described.

DESCRIPTION

FIG. 1 is a front view of the display screen of a computing device having a graphical user interface for a map application according to a first embodiment of the claimed design; and,

FIG. 2 is a front view of the display screen of the computing device having a graphical user interface for a map application according to a second embodiment of the claimed design.

The outermost solid-line rectangle illustrates the display screen of a computing device.

The broken lines illustrate portions of the graphical user interface and form no part of the claimed design.

1 Claim, 2 Drawing Sheets
